(57) **CLAIM**

The ornamental design for an exercise squat rack, substantially as shown and described in the accompanying figures.

DESCRIPTION

FIG. 1 is a perspective view of an exercise rack in accordance with the present design.

FIG. 2 is a front view of the exercise rack of FIG. 1.

FIG. 3 is a rear view thereof.

FIG. 4 is a top view thereof.

FIG. 5 is a bottom view thereof.

FIG. 6 is a left side view thereof; and,

FIG. 7 is a right side view thereof.

As indicated in the title, the article of manufacture to which the design has been applied is an exercise rack. Examples of an exercise rack are a dumbbell rack, a barbell rack, a combination rack and exercise machine such as a squat rack and exercise machine, a pull-up rack and exercise machine, and/or the like.

The broken lines showing the remainder of the exercise rack are directed to environment. None of the broken lines form a part of the claimed design.
